UNITED STATES PATENT OFFICE.

ERNST BREITLING, OF ESSEN, GERMANY, ASSIGNOR TO FRIED. KRUPP AKTIENGESELLSCHAFT, OF ESSEN-ON-THE-RUHR, GERMANY.

ZEROIZING DEVICE FOR CASH REGISTERS OR CALCULATING MACHINES.

Application filed May 18, 1922. Serial No. 561,900.

To all whom it may concern:

Be it known that I, ERNST BREITLING, residing at Essen, Germany, a citizen of the German Republic, have invented a certain 5 new and useful Improvement in Zeroizing Devices for Cash Registers or Calculating Machines, of which the following is a specification.

This invention relates to improvements in 10 cash registers or calculating machines of the kind comprising a plurality of totalizing counters, and it has more particularly reference to zero setting devices for such registers or machines.

Now, the invention has for its object to 15 provide a zero setting device for machines of the character stated which is of a construction such as to allow the totalizing counters to be simultaneously set to zero in 20 an operation of the machine following the adjustment of a zero setting member.

The accompanying drawings illustrate, 25 by way of example, an embodiment of the subject-matter of the invention as applied to a cash register comprising a plurality of totalizing counters arranged in a drum.

In the drawings:

Fig. 1 is a side elevation of the drum containing the totalizing counters and provided 30 with the zero setting device;

Fig. 2 is an elevation similar to Fig. 1, the parts being in a different position;

Fig. 3 is a longitudinal section of the drum and the zero setting gearing;

Fig. 4 is a side elevation of the arrangement of the seller's keys and the corresponding locking members;

Fig. 5 is a view similar to Fig. 4, the parts being in a different position;

Fig. 6 is a side elevation, partially in section, of the special keys for the different lines of business, of the zero setting key and the corresponding locking members;

Fig. 7 is a view similar to Fig. 6, the parts being in another position;

Fig. 8 is a section on the line 8—8 of Fig. 6.

The cash register possesses the usual amount of keys, not shown in the drawing, 50 and is besides provided with a series of seller's keys A (Figs. 4 and 5) and a series of five special keys B (Figs. 6 to 8) for the several lines of business as well as with a zero setting key B¹ arranged above the last- 55 mentioned keys. The totalizing counters C

are mounted in a drum C¹. Fastened to the shaft c² of every totalizing counter is a zero setting pinion c³ (Figs. 1 to 3). The pinions c³ are in positive connection with one another inasmuch as all of them are in mesh 60 with a toothed wheel c⁵ mounted for rotation on the drum shaft c⁴. Two integral toothed wheels d¹, d² are mounted in the casing wall D (Fig. 3) co-axially with relation to the zero-setting pinion c³ or one 65 of the totalizing counters. The toothed wheel d¹ is adapted to be coupled with the zero setting pinion c³ by means of two swingingly arranged pinions E which are fastened to a bolt e¹. The toothed wheel d² is in 70 positive connection with the main driving shaft F of the cash register by means of pinions f², f¹ (Figs. 1 and 2). The driving shaft F is provided with a crank handle f³. The bolt e¹ carrying the coupling pinions E, 75 is mounted in the arm E² of a bell crank lever E² E³, the arm E³ of which is connected by a link e⁴ to an arm e⁶ fastened to a shaft e⁵. Rigidly connected to the shaft e⁵ is another arm E⁷ which is provided at 80 its free end with a longitudinal slot e⁸ which is engaged by a pin g² of the nut g¹ of a lock G, which pin lies eccentrically with relation to the axis of rotation of the nut. The coupling pinions E are held in their 85 respective positions by means of a pawl e⁹ mounted on the lever arm E² and engaging one of the coupling pinions E under the action of a spring e¹⁰. A link e¹¹ connects the lever arm E² with an arm h¹ fastened to a 90 shaft H. The described connection of the bell crank lever E² E³ with the nut g¹ of the lock G and with the shaft H will permit the shaft H to be rocked and the coupling pinions E to be thrown into and out of 95 operative position by rotating the nut g¹.

The shaft H carries a locking cam h² (Figs. 6 and 7) which is designed to co-operate with a pin i² fastened to the arm J of a double-armed lever J J¹ which is 100 mounted in the key-bank B⁴. The lever arm J is adapted to act on a pin k¹ of a safety pawl K. The pawl K is fastened to a bolt k³. A spring k², connected to the pawl, tends to hold same in engagement 105 with a notch m¹ (Figs. 5 and 7) of a cash register locking lever M which is mounted for oscillation on a shaft m² and which, in its locking position, bears against a locking arm N¹ fastened to the cash register shaft 110

N. The lever arm J^1 is provided with an oblong slot i^3 which is engaged by a pin b^2 of the zero setting key B^1 . Each of the special keys B is provided with a pin b^3 .
 5 Provided for cooperation with the zero setting key B^1 and the special keys B are a locking plate P , a locking rocker Q and a slide R . The locking plate P is pivoted by one end to a lever m^3 arranged on the shaft m^2 and carrying the locking bar m^4 for the amount keys, while its other end is provided with a slot p^1 through which projects a guide pin b^5 arranged on the key bank B^4 . The locking plate P is provided
 10 with a slot p^2 each for the key pin b^2 and the key pins b^3 , the key pin entering the respective slot upon a key being depressed. The slot p^2 for the pin b^2 is positioned with relation to the slots p^2 for the pins b^3 in such
 15 a manner that, according to the adjustment of the locking plate P , either the zero setting key B^1 only or one of the special keys B can be depressed. The locking rocker Q is swung upwards around the shaft q^1 upon depressing a key. It is, in a well-known manner, held in this lifted position, in which it locks the depressed key, until by the striking of a setting disk S (Fig. 8) against the toe of the depressed key, the movement of this setting disk caused by the operation of the cash register, will be limited, and until the setting in the display and printing mechanism of the line-of-business mark corresponding to the
 20 depressed key caused by the setting disk, has been carried out. The slide R is pivoted by means of a pin r^1 to the prolongation m^3 of the cash register locking lever M and guided by means of its forked end
 25 r^2 on the shaft q^1 . On depressing the key B^1 or a key B , the offset b^6 of the key will strike against the slide R so that same will be pressed rearwardly against the shaft q^1 . The locking lever M is thereby oscillated around the shaft m^2 , so that it will release the cash register locking arm N^1 . In each operation of the cash register, one revolution is imparted to the shaft N carrying the locking arm N^1 . Towards the end of this
 30 revolution, a projection n^2 of the locking arm N^1 will engage a roller m^5 mounted on the locking lever M and return the latter into its starting position. A latch T mounted on a bolt t^1 of the seller's key bank A^1 (Figs. 4 and 5) and gripping, when in locking position (Fig. 4), by its hook-shaped end t^2 around the amount key locking bar m^4 serves to hold the bar m^4 against which bear the locking rockers, not
 35 shown, of the amount keys. The latch T is securely held in its locking position by a locking cam h^3 which is rigidly fastened to the shaft H and which is adapted to be placed in front of a face t^3 of the latch.
 40 If the cam h^3 takes a position opposite to a recess t^4 of the latch T , the latch is liable to be lifted. The lifting of the latch T is performed by means of the prolongation a^4 of the locking rocker A^3 of the seller's keys, a pin t^5 of the latch bearing against the said prolongation. The pin t^5 further bears on the arm U of a bell-crank lever U^1 mounted on the shaft m^2 . The lever arm U^1 carries a pin u^2 which engages a slot h^5 of an arm K^4 which is fastened to the bolt k^3 of the pawl K .
 45 The operation of the described arrangement is as follows: When ordinarily operating the cash register for the purpose of registering, the coupling pinions E are held in disengaged position (Fig. 1) by the lock G being in closing position, and the double-armed lever J J^1 is locked by the locking cam h^2 bearing against the pin i^2 of the lever, so that the zero setting key B^1 cannot be depressed. The special keys B are also locked until, by the oscillation of the locking bar m^4 caused upon setting an amount, the locking plate P pivoted to the arm m^3 will be brought into a position such as to cause the slots p^2 to be placed in the path of the key pins b^3 . In these operations of the cash register, the release of the cash register locking lever M is performed by disengaging the safety pawl K from the notch m^1 of the locking lever M , which disengagement is caused through the intermediary of the prolongation a^4 , the pin t^5 , the bell crank lever U^1 , the pin u^2 , the arm K^4 and the bolt k^3 through the locking rocker A^3 being swung upwardly when depressing a seller's key A . At the same time, the latch T has been lifted and the amount key locking bar m^4 released by the action of the prolongation a^4 on the pin t^5 . This movement of the latch T is possible because the locking cam h^3 lies oppositely to the recess t^4 (Fig. 5). Now, the amount being set and, thereupon, the cash operating drive released by depressing a special key B , the offset b^6 of the key pushes the slide R backward and rocks thereby the released locking lever M in such a manner that it releases the cash register locking arm N^1 . When operating the cash register, the totalizing counter C corresponding to the depressed seller's key is coupled, for the purpose of registration, with the amount key setting disks (not shown) while these are being returned to their starting position.
 50 In order to set the totalizing counters to zero, the lock G is opened. In doing so, the nut g^1 is turned and a swinging movement imparted to the arm E^1 , which swinging movement is transmitted by means of the shaft e^5 , the arm e^6 and the link e^4 to the bell crank lever E^2 E^3 and which causes the coupling pinions E to be brought into engagement with the toothed wheels d^1 and d^2 . At the same time, the shaft H will be
 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

rocked by means of the arm h^1 connected through the link e^{11} to the bell crank lever $E^2 E^3$, in such a manner (Fig. 2) that the locking cam h^2 releases the pin i^2 and along 5 with same the lever $J J^1$ as well as the zero setting key B^1 (Fig. 7). Also, the locking cam h^3 is placed in front of the face t^3 of the latch T , so that the latter is locked in its locking position in which it holds the 10 locking bar m^4 for the amount key locking rockers and the prolongation a^4 of the seller's key locking rocker A^3 . The locking plate P , which is pivotally connected to the locking bar m^4 , is thus held in a position in 15 which the zero setting key B^1 but none of the special keys B can be depressed. The release of the cash register locking lever M for the zero setting cash register operations takes place in the first part of the 20 movement of depression of the key B^1 , the safety pawl K being disengaged from the notch m^1 of the locking lever M by the action of the arm J of the lever $J J^1$ on the pin h^1 . In the further course of the movement 25 of the key B^1 , its offset b^6 will strike against the slide R and, in the same manner as afore described with relation to a special key, it will cause the released locking lever M to rock in such a manner as to release 30 the cash register locking arm N^1 . Thereupon, one revolution is imparted to all of the totalizing counter shafts c^2 which are coupled with the cash register driving shaft F through the toothed wheels $c^3, c^5, E, d^1, d^2, f^2, f^1$, for the purpose of simultaneously setting them to zero. The zero setting cash operation can also be utilized to set a mark, influenced by the zero setting key, in the display and printing mechanism 40 in a manner such as is well known for setting a seller's mark.

Claims:

1. In a machine of the character stated, comprising an operating mechanism, a main driving shaft, a plurality of totalizing counters and zero setting pinions connected with the totalizing counters, a zero setting member, a driving member for simultaneously actuating the zero setting pinions of all totalizing counters and a member in the operating mechanism adapted to be moved by the main driving shaft and to be coupled with the said driving member upon adjusting the zero setting member, for the purpose 55 of setting the totalizing counters to zero in the operation of the machine following the adjusting of the zero setting member.
2. In a machine of the character stated, comprising an operating mechanism, a main 60 driving shaft, a plurality of totalizing counters and zero setting pinions connected

with the totalizing counters, setting members including a zero setting member, a driving member for simultaneously actuating the zero setting pinions, and a member in the 65 operating mechanism adapted to be moved by the main driving shaft, a lock for normally locking the zero setting member in inoperative position, said lock when unlocked allowing the zero setting member to 70 be released, the afore-said member of the operating mechanism to be coupled with the driving member for the zero setting pinions and the other setting members of the machine to be locked. 75

3. In a machine of the character stated, comprising an operating mechanism, a main driving shaft, a plurality of totalizing counters and zero setting pinions connected with the totalizing counters, setting members including a zero setting member, a driving member for simultaneously actuating the zero setting pinions, and a member in the 80 operating mechanism adapted to be moved by the main driving shaft, a lock for normally locking the said zero setting member in inoperative position, the nut of said lock being positively connected to a lever which is provided with pinions for coupling the zero setting pinions with the operating 85 mechanism of the machine and which is positively connected to a shaft carrying locking cams adapted to lock locking members for the zero setting member and the other setting members of the machine in their 90 locking position. 95

4. In a machine of the character stated, comprising an operating mechanism, a main driving shaft, a plurality of totalizing counters and zero setting pinions connected to the totalizing counters, amount keys, special keys, seller's keys and a zero setting key, a driving toothed wheel meshing with and adapted to simultaneously actuate the zero setting pinions, and another toothed wheel in the operating mechanism adapted to be rotated by the main driving shaft, a lock for normally locking the zero setting key in inoperative position, the nut of said lock being positively connected to a bell 100 crank lever which is provided with pinions for coupling the zero setting pinions with the said toothed wheel of the operating mechanism of the machine and which is positively connected to a shaft carrying locking cams adapted to lock locking members for the zero setting key, the amount 105 keys, special keys and seller's keys. 110

The foregoing specification signed at Essen, Germany, this 24th day of April, 1922.

ERNST BREITLING.
